R. M. HOPKINS,
SIGNAL TRANSMITTER.
APPLICATION FILED OCT. 10, 1919.

1,406,865.

Patented Feb. 14, 1922.

INVENTOR.
Richard M. Hopkins
H. M. MARBLE
ATTORNEY.

UNITED STATES PATENT OFFICE.

RICHARD M. HOPKINS, OF RUTHERFORD, NEW JERSEY, ASSIGNOR TO AMERICAN DISTRICT TELEGRAPH COMPANY, OF JERSEY CITY, NEW JERSEY, A CORPORATION OF NEW JERSEY.

SIGNAL TRANSMITTER.

1,406,865.

Specification of Letters Patent. Patented Feb. 14, 1922.

Application filed October 10, 1919. Serial No. 329,720.

To all whom it may concern:

Be it known that I, RICHARD M. HOPKINS, a citizen of the United States of America, and resident of Rutherford, county of Bergen, and State of New Jersey, have invented 5 Improvements in Signal Transmitters, of which the following is a specification.

My invention relates to improvements in signal transmitters, particularly that type 10 thereof employed especially in transmitters of the "call-box" type, which operate both by breaking and closing a line circuit, and by closing and breaking a ground-return circuit. In the art, such transmitters are commonly termed "McCulloh" transmitters. In 15 the types of McCulloh transmitters most commonly used, two signal wheels, with corresponding contact springs, are employed, one signal wheel, with its corresponding 20 contact springs, being employed for breaking and closing the line circuit, the other signal wheel and its corresponding contact springs, being employed for closing and breaking the ground connection; both signal wheels being 25 commonly mounted upon the same rotating shaft. In the construction embodying my present invention, however, one signal wheel only is employed, from which fact, and from the simplified arrangement of contact 30 springs employed, much simplification results. My invention consists in a novel arrangement of contact springs in connection with a single signal wheel, as hereininafter described and particularly pointed out 35 in the appended claims.

The object of my invention is to simplify signal transmitters of the type referred to.

I will now proceed to describe my invention with reference to the accompanying 40 drawings, and will then point out the novel features in claims.

In said drawings:

Figure 1 is a diagrammatic view illustrative of the arrangement of contact springs 45 in connection with the signal wheel and circuits;

Figure 2 is a face view of the transmitter, the enclosing case being omitted;

Figure 3 is a side view of the transmitter, and

Figure 4 a fragmentary side view showing the parts in a position different from that shown in Figure 2.

Figure 5 is a fragmentary side view of

contact springs, illustrating an alternative 55 arrangement.

In the drawings, 1 designates the frame of the instrument, 2 a main spring, 3 a winding handle therefor, and 4 a gear train driven by spring 2, and by which motion is communicated to a cam 5 and also to a signal wheel 6. The general construction, as so far described, is well known, and does not differ from that commonly employed in signal transmitters of the type referred to, and 60 therefore I do not deem it necessary to describe it here in greater detail. It will be understood that when the handle 3 is pulled down and then released, motion is communicated through the gear train to the cam 5 65 and also to the signal wheel 6.

7 designates a contact spring or "pen" as it is termed in the art, normally out of contact with the teeth of wheel 6, but adapted to make contact with the teeth of said wheel 70 as the latter pass its tip. As appears from Figure 1, pen 7 is connected by conductors 8 and 9 to an external circuit connection 10 (which is one terminal of the line circuit). The wheel 6 itself is in electrical connection 75 with the frame of the apparatus, and therefore with ground; 11 (Figures 1 and 2) being a ground connection. Obviously, circuit will be completed from 10 through 9, 8 and 7, to ground, only when pen 7 is in contact 80 with a tooth of signal wheel 6.

12, 13 and 14 are other contact springs, of which 12 is arranged to be actuated by the teeth of signal wheel 6, and, when raised by one of said teeth, is caused to be elevated 90 from spring 13, which spring 13 thereupon breaks contact with spring 14; spring 12 being a mere actuator for spring 13. This spring 13 is connected, like pen 7 through conductors 8 and 9, with line terminal 10. 95 Spring 14 is connected with another line terminal 15.

In the particular construction shown, the contact springs 7, 12, 13 and 14, are all mounted upon a movable member 16, pivoted at 16^a and provided with a toe 16^b adapted to be engaged by cam 5, in such manner that while normally the pens 7 and 12 are clear of the teeth of wheel 6, yet soon after wheel 6 begins to rotate, cam 5 moves carrier 100 16 to bring springs 7 and 12 into the path of the teeth of wheel 6. This, however, is a mere feature of the particular transmitter 105

illustrated, and is not a feature of the invention, or necessary to the invention. It is common in the art to have contact springs mounted to be permanently in the path of movement of the teeth of the signal wheel, and the arrangement of contact springs shown is clearly applicable to such cases. Likewise, in the drawings, contact springs 17 and 18, actuated by a secondary cam 19, are provided; but these contact springs and cam are a mere feature of the particular transmitter indicated in the drawings, and have nothing to do with the present invention.

According to the present invention, in the operation of the transmitter the teeth of wheel 6 successively engage spring 12, thereby lifting said spring away from spring 13, and permitting said spring 13, by its natural resilience, to separate from spring 14, thereby breaking the line circuit, of which 10 and 15 are terminals, as previously explained. As soon as a tooth of wheel 6 has passed beyond the top of spring 12, the latter drops, by its natural resilience, again bringing together springs 13 and 14, and so closing the line circuit so far as this transmitter is concerned. The length of spring 7 is such that when springs 13 and 14 are so in contact during the spaces between teeth of wheel 6, the tip of pen 7 engages a tooth of the wheel 6, so completing a ground connection; that is to say the relation between the lengths of pens 7 and 12, with respect to the spacing of the teeth of the signal wheel, is such that contact of ground pen 7 with a tooth of the signal wheel occurs while pen 12 is out of engagement with any tooth of the signal wheel; and, conversely, engagement of any tooth of the signal wheel with pen 12 occurs when pen 7 is not in engagement with any tooth of the signal wheel. Of course there are periods, corresponding to the spaces between tooth groups of the signal wheel, when neither pen 7 nor pen 12 is engaged by any tooth of the signal wheel.

It will be seen that by causing both the ground pen 7 and the line pen 12, to coact with the teeth of the same signal wheel, and by so arranging these pens that coaction of each of said pens 7 and 12 with a tooth of that signal wheel occurs while the other of said pens is not in engagement with any tooth of that signal wheel, I effect breakage of the line circuit by the one contact device, and closing of the ground connection by the other contact device, without mutual interference by either contact device with the action of the other.

In transmitters such as heretofore employed for McCulloh operation, and employing two separate signal wheels, it is commonly necessary to insulate one wheel from the other; by employing a single signal wheel for both the line contact and the

ground contact, according to the present invention, not only is the second signal wheel of the ordinary McCulloh box eliminated, but also the corresponding insulation between the wheels is eliminated, which in turn eliminates various other parts, and furthermore makes the assembly and adjustment of the required parts much more easy, and reduces many sources of possible trouble; moreover, the shape and arrangement of this spring as herein illustrated is much simpler than that in the former boxes referred to; for example, all of the contact springs of the present invention may be in one plane, whereas in the double wheel arrangement of former McCulloh boxes, the contact springs for the one signal wheel must commonly be in a plane separate from that in which contact springs of the other wheel are located. The wiring is also much simplified.

It is apparent that instead of pen 7 making electrical contact with the teeth of the signal wheel, this pen may actuate other contact springs, just as pen 12 actuates contact springs 13 and 14. This is illustrated in Figure 5, wherein the pen is designated by numeral 7^a, the contact springs which it actuates being designated by 20 and 21. This arrangement is the mere equivalent of the arrangement wherein pen 7 makes electrical contact with wheel 6.

What I claim is:

1. A signal transmitter comprising a single toothed signal wheel, and means for driving same, in combination with two separate contact devices arranged to be engaged by the teeth of said signal wheel, one of said contact devices comprising an actuating element by engagement of which with the teeth of said signal wheel that contact device is operated, the other of said contact devices arranged to engage said teeth during periods when the actuating element of the first mentioned contact device is between teeth of said signal wheel and is not being actuated by said teeth.

2. A signal transmitter such as described comprising a toothed signal wheel, such as 6, and means for driving the same, in combination with two separate contact devices, such as 7 and 12, 13-14 respectively, arranged to coact with said signal wheel, the member 7 arranged to be engaged by the teeth of said signal wheel during periods when the member 12 is not engaged by said teeth, and vice versa.

In testimony whereof I have signed this specification in the presence of two subscribing witnesses.

RICHARD M. HOPKINS.
